OF NO 17,203

DESIGN.

F. MANKEY.

PANEL.

No. 17,203.

Fig. 2. Patented May 22, 1887.

UNITED STATES PATENT OFFICE.

FREDERICK MANKEY, OF WILLIAMSPORT, PENNSYLVANIA.

DESIGN FOR A PANEL.

SPECIFICATION forming part of Design No. 17,203, dated March 22, 1887.

Application filed December 30, 1886. Serial No. 293,051. Term of patent 7 years.

To all whom it may concern:

Be it known that I, FREDERICK MANKEY, of Williamsport, Lycoming county, Pennsylvania, have invented and produced a new and 5 original Design for Panels, of which the following is a specification, reference being had to the accompanying photographs, forming part hereof.

Figure 1 represents my new design, and 10 Figs. 2 and 3 modifications thereof.

Similar letters of reference indicate like parts.

My design consists in the raised parallelogram-shaped elevation A, the edges or sides B 15 of which appear in the form of steps. Parallel to the elevation A are two rectangular elevations, C C', also having sides or edges D in the form of steps. The upper surface of said elevations is flat, and each has the general appearance of a series of elevations superposed and gradually diminishing in area. The number of steps upon the sides or edges of said elevations is here shown as four, and should always be more than two. Between the elevations A and C and C' are channels F. I may 20

show as a segregable and distinct portion of my design only the elevation A and elevation C, as in Fig. 2; or I may repeat my said design, as shown in Fig. 3, modifying the same by reducing the width of said elevations. 30

I claim—

1. The design for a panel, substantially as herein shown and described, which consists in the rectangular elevation A, the rectangular elevation C, and the intermediate channel, F, 35 the sides or edges B D of said elevations appearing in the form of steps greater in number than two.

2. The design for a panel, substantially as herein shown and described, which consists in 40 the rectangular elevation A, the rectangular elevations C C', and intermediate channels, F F', the sides or edges of said elevations appearing in the form of steps greater in number than two.

FREDERICK MANKEY.
